UNITED STATES PATENT OFFICE.

CHARLES T. CHILDERS, OF GALESBURG, ILLINOIS.

CAMPAIGN HORN AND RATTLER.

SPECIFICATION forming part of Letters Patent No. 728,083, dated May 12, 1903.

Application filed April 2, 1903. Serial No. 150,773. (No model.)

To all whom it may concern:

Be it known that I, CHARLES T. CHILDERS, a citizen of the United States, residing at Galesburg, in the county of Knox and State of Illinois, have invented certain new and useful Improvements in Campaign Horns and Rattlers, of which the following is a specification.

This invention relates to an improvement in sounding toys, and has special reference to a combined horn and rattle possessing special utility for campaign and analogous demonstrations, while at the same time subserveing a generally useful function as a toy.

To this end the invention contemplates a simple, inexpensive, and practical device of the character specified of a collapsible nature, whereby the same will occupy when collapsed a very small compass, so that it can be conveniently handled in small packages and can be handily carried about in a pocket for use when desired. At the same time the invention has in view a toy embodying means for providing a complete sounding horn or trumpet and also a complete rattle made up of members of the flaring sound-tube of the horn.

With these and many other objects in view, which will more readily appear as the nature of the invention is better understood, the same consists in the novel construction, combination, and arrangement of parts, which will be hereinafter more fully described, illustrated, and claimed.

The essential features of the invention involved in the construction providing for the convertibility of the device from a horn to a rattle, and vice versa, are necessarily susceptible to modification in structure without departing from the scope of the invention; but a preferred embodiment thereof is shown in the accompanying drawings, in which—

Figure 1 is a sectional view of a combination horn and rattle with the parts assembled in the positions they occupy when providing a complete horn used in the manner of an ordinary toy tin horn. Fig. 2 is a sectional view of the same device, showing the telescopic sound-tube collapsed, with the sections thereof sustained upon the supporting-base in position to provide rattling elements

which may be vibrated against each other to produce a rattling sound. Fig. 3 is a top plan view of the rattle shown in Fig. 2.

Like reference-numerals designate corresponding parts throughout the several figures 55 of the drawings.

In carrying out the invention the general outlines of a common toy or tin horn are preserved, so that when used simply as a horn for campaigning or other purposes the device 60 appears as the common type of horn. The construction, however, is of such a nature that the device can be readily converted into a rattle, as may be plainly seen from the drawings, to which particular reference will 65 be made.

To provide a medium for supporting the sections or members constituting the horn, as well as the rattling elements, the invention involves the employment of a supporting-base, (designated by the numeral 1,) which is preferably in the form of a concavo-convex disk provided at one side thereof with an interiorly-threaded offset socket 2, in which is detachably threaded the exteriorly-threaded 75 joint-neck 3 of a tapered tubular mouthpiece 4. This mouthpiece 4 may be the ordinary simple type of mouthpiece, such as commonly employed in connection with the ordinary tin horn, and has arranged therein any 80 approved and simple form of sounding whistle or reed 5, whereby the sound may be produced and reflected through the main tube of the device when employed solely as a horn. When the device is converted into a rattle 85 and is held in an upright position, the mouthpiece 4 constitutes a hand-grip or handle by means of which the rattle or rattle may be operated. At the side of the supporting-piece opposite the detachable combined 90 mouthpiece and handle 4 the said supporting-base is designed to carry a collapsible telescopic sound-tube 6. This collapsible or telescopic sound-tube 6 is made up of a series of frusto-conical tube-sections 7 of successively 95 increasing size, fitting one within the other and having a telescopic connection with each other, so that when drawn out to their extreme limit the same provide a complete extended flared tube or horn-body through 100

which the sound is carried from the whistle or reed of the mouthpiece when the device is employed as a horn. The innermost telescopic tube-section 7 (designated by the numeral 7^a) is rigidly fitted in a central opening of the supporting-base 1, and the outermost section (designated by the numeral 7^b) is in the form of the bell usually provided at the outer end of a horn or trumpet tube.

- 10 When it is desired to convert the device into a rattle, the telescopic sections 7 are collapsed upon the base 1, so that when the device is turned in an upright position all of the said sections loosely and disconnectedly 15 rest upon the base 1, so that by grasping the combined handle and mouthpiece element 4 in the hand and shaking or vibrating the same the tube-sections 7 become rattling elements and provide a rattling noise as they 20 are jingled or vibrated against each other.

From the foregoing it is thought that the construction, use, and many advantages of the herein-described horn and rattle will be readily apparent without further description, 25 and it will also be understood that changes in the form, proportion, and minor details of construction may be resorted to without departing from the spirit of the invention or sacrificing any of the advantages thereof.

30 Having thus described the invention, what

is claimed, and desired to be secured by Letters Patent, is—

1. A sounding toy of the class described having a body convertible from a horn into a rattle, and vice versa. 35

2. A toy of the class described comprising a body having members forming sections of a horn-tube and also forming elements of a rattle.

3. A toy of the class described comprising 40 a body having a collapsible member forming a horn-tube and also elements of a rattle.

4. A combined horn and rattle comprising a supporting-base carrying a collapsible sound-tube, and a combined handle and 45 mouthpiece.

5. A combined horn and rattle comprising a supporting-base carrying at one side thereof a collapsible telescopic flaring sound-tube whose sections constitute rattling elements 50 adapted to be loosely sustained upon the base, and a sounding-mouthpiece also carried by the supporting-base and constituting a handle for the toy when employed as a rattle.

In testimony whereof I affix my signature 55 in presence of two witnesses.

CHARLES T. CHILDERS.
